UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 34,270, dated March 26, 1901.

Application filed April 12, 1900. Serial No. 12,639. Term of patent 7 years.

To all whom it may concern:

Be it known that I, CHARLES J. AHRENFELDT, a citizen of the United States, residing at the city of New York, county of New York, and State of New York, have invented and produced a new and original Design for a Plate or Similar Article, of which the following is a specification, reference being had to the accompanying drawings, forming a part thereof.

In the said drawings, Figure 1 is a plan view of a plate with my design placed thereon. Fig. 2 is a cross-section thereof.

The panels A consist of a wreath A' of flowers and leaves hung from a knotted ribbon A² and having a cluster of like flowers and leaves A³ in the center thereof.

The panels A are connected by streamers of leaves and flowers B B', hung from pairs of roses b b' and intersecting each other, a pair of roses B² being located at each point of intersection.

The centerpiece C consists of a cluster of roses C' at the center, with leaves and small flowers c, resembling forget-me-nots, projecting from each rose. From this central cluster proceed loops C² of small leaves and flowers resembling forget-me-nots, presenting a petal-like appearance, and provided at their outer parts with a pair of roses C³. Opposite the points where the loops or petals converge are small flowers and leaves C⁴ of the same variety.

What I claim is—

The design for a plate or similar article substantially as herein shown and described.

Signed at the city of New York, in the county of New York and State of New York, this 14th day of March, 1900.

CHARLES J. AHRENFELDT.
